UNITED STATES PATENT OFFICE.

WILLIAM HENRY DAWSON AND JAMES STOTT, OF OTLEY, ENGLAND.

PRINTING-MACHINE.

SPECIFICATION forming part of Letters Patent No. 689,066, dated December 17, 1901.

Application filed April 10, 1901. Serial No. 55,239. (No model.)

To all whom it may concern:-

Be it known that we, WILLIAM HENRY DAWSON and JAMES STOTT, subjects of the King of Great Britain and Ireland, residing at Otley, in the county of York, England, have invented a new and useful Improvement in Printing-Machines, of which the following is a specification.

This invention relates to printing-machines; and it consists in the novel construction and combination of the parts hereinafter fully described and claimed.

In the drawings, Figure 1 is a partial section of the cylinder and the devices coöperating with it. Fig. 2 is an end view of the cylinder and the parts coöperating with it. Fig. 3 is a plan view of the same.

A is an impression-cylinder, which is journaled in a frame 10.

D is the type-bed, which reciprocates in the frame 10 and is provided with a toothed rack C, which gears into a toothed wheel B on the cylinder, so that the said cylinder is oscillated as the bed is moved back and forth.

R' is the feed-board for the sheets of paper. S' is the stop.

T' is a pivoted switch.

P' and Q' are rolls for removing the printed sheets.

O' is a presser-roll carried by a shaft N'. E' represents gripper-fingers secured on a shaft F', which is mounted in the cylinder.

K' represents lifter-fingers secured on a shaft L' and projecting over the shaft F'. The shaft F' is operated by means of a lever 3, having its middle portion secured on the shaft F' at one end of the cylinder A.

G' and I' are rolls carried by the respective ends of the lever 3 on opposite sides of the shaft F'. The shaft L' is operated by a lever 4, which carries a roller M', said lever being secured on the said shaft adjacent to the lever 3.

H' is a cam-bar pivoted at one end on a pin 45 H², which projects from the frame 10. The other end of the cam-bar H' has an operating arm or rod 1 pivoted to it. The cam-bar H' is placed in the path of the roll G and operates to lower the gripper-fingers E'.

J' is a cam-bar pivoted on a pin projecting from the frame 10, and this cam-bar is pro-

vided with an arm 2 for operating it. The cam-bar J' is arranged in the paths of the rolls I' and M', and it raises the gripper-fingers E' and the lifter-fingers K'.

55

All the above-mentioned parts are operated by any approved driving mechanisms. These parts all operate in the usual manner. The sheet of paper slides down the feed-board R' against the stop S', and its edge is seized by the gripper-fingers E'. The sheet is carried around the cylinder and is printed upon in the usual manner. After making a little more than a full revolution the front edge of the sheet is run over the point of the switch 60 T', the said switch being depressed at the proper moment and the gripper-fingers E' and the lifter-fingers K' raised at the same time. The sheet slides over the switch T' and passes between the rolls P' and Q' and is carried 70 away.

In order to increase the capacity of the machine, a second shaft F is mounted in the cylinder parallel with the shaft F'. The shaft F has gripper-fingers E secured on it and projecting in the opposite direction from the gripper-fingers E'.

L is a shaft mounted in the cylinder adjacent to the shaft L', and K are lifter-fingers which are secured on the shaft L and which 80 project over the shaft F.

R is a feed-board arranged on the opposite side of the cylinder-shaft from the feed-board R' and provided with a separate stop S.

T is a pivoted switch arranged on the opposite side of the cylinder from the switch T' and provided with rolls P and Q for removing the printed sheets.

O is a presser-roll carried by a shaft N, similar to the roll O' and shaft N', but arranged under the switch T.

The shaft F is provided with an operating-lever 3' at the opposite end of the cylinder from the lever 3, and the shaft L is provided in a similar manner with an operating-lever 4'. The levers 3' and 4' are provided with rolls G', I', and M', the same as the levers 3 and 4, and these levers are operated by means of cam-bars exactly the same as hereinbefore described with reference to the levers 3 and 4.

95 100
The two sets of mechanisms operate alternately, and the sheets are taken from the

feed-boards R and R' alternately, according to the direction of the motion of the cylinder.

What we claim is—

The combination, with an oscillatory im-
5 pression-cylinder, of shafts F and F' provided
with gripper-fingers and mounted in the cyl-
inder, shafts L and L' provided with lifter-
fingers and also mounted in the cylinder, an
operating-lever 3' having its middle part se-
10 cured to the shaft F at one end of the cylin-
der and provided with a roller at each end, a
lever 4' secured to the shaft L adjacent to the
lever 3' and provided with a single roller, an
operating-lever 3 having its middle part se-
15 cured to the shaft F' at the other end of the

cylinder and provided with a roller at each
end, a lever 4 secured to the shaft L' adjacent
to the lever 3 and provided with a single
roller, and separate cam-bars at each end of
the cylinder arranged in the paths of the 20
rollers to which they pertain, substantially
as described and shown.

In testimony whereof we have signed our
names to this specification in the presence of
two subscribing witnesses.

WILLIAM HENRY DAWSON.
JAMES STOTT.

Witnesses:

JOSEPH MASON,
JAMES HAYWOOD.
